United States Patent Office.

ALLEN O. DIVINE, OF CAMBRIA MILLS, MICHIGAN.

Letters Patent No. 64,289, dated April 30, 1867.

IMPROVEMENT IN GATES.

The Schedule referred to in these Letters Patent and making part of the same.

TO ALL WHOM IT MAY CONCERN:

Be it known that I, A. O. DIVINE, of Cambria Mills, in the county of Hillsdale, State of Michigan, have invented a certain new and useful Improvement in Gates; and I do hereby declare that the following is a full and exact description thereof, reference being had to the accompanying drawings making part of this specification, in which—

Figure 1 is a perspective view of my improved gate.

Figure 2, a plan view of the same when folded and swung open.

My improved gate is designed more especially for farm purposes; and the invention consists in hinging the gate at the centre, so that one-half may be opened, when required, without disturbing the other portion, and the full passage opened by partially sliding back the gate, swinging it around, and folding the two portions together, as hereinafter fully described.

In the drawings, A B represent the two portions of my gate, hinged together at the centre in any suitable manner, so that the portion A may be opened by swinging around when only a narrow passage is required, as shown in red lines, fig. 1. The portion B is mounted between two posts, C D, and supported by one of its boards, E, resting upon a small friction-wheel, f, in the upper edge of the cross-piece g, which connects the two as shown. At the centre the gate is supported by a friction-roller, h, mounted in the bottom of the upright or cross-piece I of the portion B, which operates in a suitable way, m, secured to the bed-piece O, or formed therein.

When the entire gate is required to be opened it is first slid back, as represented in red lines, disengaging the roller from the way m, when the gate is swung around, and the parts A B at the same time folded together in the position shown in fig. 2, where, if required, it may be fastened by a hook, s, attached to the post D, which catches over one of the boards. By making one side of the way m at the rear shorter than the other, the longer side will act as a stop for the roller h, so that in swinging the gate around in closing it the roller will strike against the longer side, as shown in red lines, and thence be readily guided by the same into the way, when the gate is slid forward and parts A B unfolded, again closing the passage. In the majority of instances when a passage is required, one of narrow width, that will admit a man or beast, is sufficient. By the use of my improvement such a passage can be readily effected by simply opening the portion A, without the labor and inconvenience of sliding back and opening the whole gate, which, in passages that are much used, becomes a matter of considerable importance. My improvement also secures the advantage of enabling the gate to be opened to its full width with much less effort than usual, as, when the part A is swung open on its hinged axis, it is only required to slide the part B half its length, when the whole gate is balanced on the pulley f and swings around with slight effort to open the passage fully. This construction makes it more compact than other gates of equal width, and enables it to be used in many situations where there is not space to swing or slide a gate of full length.

What I claim, and desire to secure by Letters Patent, is—

A gate constructed of the hinged parts A B, as described, in combination with the way m, friction-rollers h and f, and catch s, so arranged as to form at once a swinging, sliding, and folding gate, substantially as set forth.

In witness whereof I have hereunto signed my name in the presence of two subscribing witnesses.

ALLEN O. DIVINE.
